Zhang, B., "Pen," U.S. Appl. No. 29/386,543, filed Mar. 2, 2011.

Primary Examiner — Elizabeth Albert

(74) Attorney, Agent, or Firm — Christensen O'Connor Johnson Kindness PLLC

(57) **CLAIM**

The ornamental design for a pen, as shown and described.

DESCRIPTION

FIG. 1 is a lower front left perspective view of a pen showing my new design;

FIG. 2 is a right side elevation view thereof, with the left side elevation view being a mirror image of the right side elevation view;

FIG. 3 is a front elevation view thereof;

FIG. 4 is a rear elevation view thereof;

FIG. 5 is an enlarged top plan view thereof; and,

FIG. 6 is an enlarged bottom plan view thereof.
